UNITED STATES PATENT OFFICE.

ARTHUR MARTIN, OF PARIS, FRANCE.

DESIGN FOR WALL-PAPER.

SPECIFICATION forming part of Design No. 28,110, dated December 28, 1897.

Application filed October 26, 1897. Serial No. 656,469. Term of patent 7 years.

To all whom it may concern:

Be it known that I, ARTHUR MARTIN, of Paris, France, have invented and produced a new and original Design for Wall-Paper, of which the following is a specification, reference being had to the accompanying drawing, forming a part thereof, in which is represented a plan view of a fragment of wall-paper embodying the new design.

○ The design which is produced upon wall-paper X simulates a growing plant of pinks and in the grouping of the stems and flowers of the plant and in the relation of the several plants to each other. The lower portion of the stem A of one plant appears to rise from a flower B at the upper portion of the adjacent plant, forming a chain of plants. In the

drawings of the plants a number of flowers are massed at the center and lateral stems extend from behind the mass of flowers upwardly in direction of the sides of the plant, while another branch supports a flower between the side branches, the stem of the next plant appearing to commence adjacent to this flower. Other branches having flowers connect with the parent stem below the central mass of bloom.

I claim—

The design for wall-paper herein shown and described.

ARTHUR MARTIN.
